UNITED STATES PATENT OFFICE.

WILLIAM J. LORCH, OF CORNWALL-ON-THE-HUDSON, NEW YORK.

SUPPORTING MEANS FOR HOSE-CLAMPS.

1,297,483.

Specification of Letters Patent. Patented Mar. 18, 1919.

Application filed February 21, 1917. Serial No. 150,073.

To all whom it may concern:

Be it known that I, WILLIAM J. LORCH, citizen of the United States of America, residing at Cornwall-on-the-Hudson, in the 5 county of Orange, State of New York, have invented certain new and useful Improvements in Supporting Means for Hose-Clamps, of which the following is a specification.

10 My invention relates to means for supporting a hose clamp, particularly for use in connection with fire extinguishing apparatus.

In Letters Patent Number 1,219,968, is 15 sued to me on March 20, 1917, I have illustrated and described a hose clamp with means for supporting the same on a fire ladder. The supporting means shown in said patent consists substantially of sockets 20 which are held by the side bars of the ladder.

I have found in practice that, while this form of supporting means is satisfactory for certain purposes, it is susceptible of improvement in so far as removability of the support, and its portability is concerned.

The object of the present invention is to provide a novel form of supporting means for a hose clamp, and while the invention 30 may be applied to any form of hose clamp, I have shown it in connection with the special form of hose clamp disclosed by my aforesaid patent.

The invention is illustrated in the accompanying drawing, in which—

Figure 1 is an elevational view of a section of a fire ladder with the hose clamp and supporting means therefor in position between adjacent rungs;

40 Fig. 2 is a vertical sectional view on the line 2—2 of Fig. 1; and

Fig. 3 is a fragmentary perspective view of a detail.

In the drawing, the side bars of the ladder 45 are denoted 10 and the two rungs are denoted 11 and 12.

The hose clamp, as herein illustrated, 50 comprises a yoke 13 having oppositely disposed latching means 14 to receive pins 15 projecting from the nozzle of the hose 16.

The support for the hose clamp comprises the parallel bars 17 having their upper ends formed into hooks 18 adapted to take over

one of the rungs, such as that denoted 11. The lower end of each bar 17 is bifurcated 55 to form a fork 19 designed to be passed over the adjacent rung 12.

The bars 17 are suitably held together by means of a cross brace 20 the opposite ends of which are preferably riveted at 20^a to the 60 hooked ends 18. To impart strength to the bars, and increase their rigidity, each thereof is preferably twisted adjacent its ends, as indicated at 17^a.

The jaws which constitute the hooks 18 65 are orificed to receive a locking pin 21, as more clearly shown in Fig. 3. One of the jaws, preferably that which is immediately at the top of the bar 17 is provided with an orifice 22, preferably of annular form, connected with a rectangular slot 22^a, and the locking pin 21 is provided at an intermediate point with a lug 21^a and at its end with a lever or handle 23. To lock the support 70 in position, the pin 21 is inserted into the orifice 22 with the lug 21^a in line with the slot 22, and when the lug 21^a has passed the slot 22 the handle 23 may be released whereupon the pin 21 will rotate and the lug 21^a 75 will prevent the pin 21 from being pulled 80 out.

Near the handle 23, upon the pin 21, are two collars 24 between which is a ring 25 loosely mounted and carrying a chain 26 which is attached to the bar 17. 85

It will be noted that the fork 19 is of considerable depth, whereby the device is useful for ladders in which the distance between the rungs varies considerably. Owing to the fact that the hooks 18 may be securely 90 locked in position by the pin 21, there is no danger of the supporting device working loose, so long as a rung is between any portion of the jaws or arms which constitute the fork 19. 95

The hose clamp is provided with laterally projecting gudgeons 27 which are pivotally mounted in the side bars 17.

The device is used in the following manner:—After the hose clamp is in position in 100 the side bars 17, forks 19 are dropped on to a rung of the ladder and the hooks 18 dropped over the next adjacent rung. Thereafter the pins 21 are inserted into the orifices 22—22^a and the device is ready for 105 use. To remove the structure the pins 21

are withdrawn from the orifices 22—22^a and the device as an entirety may be lifted off the rungs 11 and 12.

What I claim is:—

- 5 1. In supporting means for hose clamps, the combination with a pair of oppositely disposed parallel bars each having a bearing intermediate the ends, of a hose clamp having oppositely projecting pins revoluble in 10 said bearings whereby said clamp is revolvably supported by said bars, a fork at one end of each bar and a hook at the opposite end thereof, and means for releasably locking said hooks to a rung of a ladder,
- 15 2. In supporting means for hose clamps, the combination with a pair of oppositely disposed parallel bars each having a bearing intermediate its ends, of a hose clamp having oppositely projecting pins revoluble

in said bearings whereby said clamp is revolvably supported by said bars, a fork at one end of each bar and a hook at the opposite end thereof, and means for releasably locking said hooks to a rung of a ladder, comprising aligned perforations in the members or legs of said hooks, one of said perforations having a rectangular slot connected therewith, and a locking pin having thereon an angular leg adapted to be passed through said slot when said pin is in a given position 30 in relation to said hook.

In testimony whereof I have affixed my signature in presence of two witnesses.

WILLIAM J. LORCH.
